(57) **CLAIM**

The ornamental design for an audio speaker enclosure, as shown and described.

DESCRIPTION

FIG. 1 is a top and front view of an audio speaker enclosure showing my new design;

FIG. 2 is a top and rear view thereof;

FIG. 3 is a top and front view of a second embodiment of FIG. 1; and,

FIG. 4 is a top and front view of a third embodiment of FIG. 1.

The bottom view is flat and devoid of surface ornamentation.
